United States Patent Office

Des. 184,888
Patented Apr. 14, 1959

184,888

DISH

Julia J. Pickett, Indianapolis, Ind.

Application November 1, 1957, Serial No. 48,303

Term of patent 3½ years

(Cl. D44—15)

Fig. 1 is a plan view of a dish, showing my new design; and

Fig. 2 is a vertical section taken on the line 2—2 of Fig. 1.

I claim:

The ornamental design for a dish, as shown.
